UNITED STATES PATENT OFFICE.

WILLIAM R. SCOTT, OF BERKELEY, CALIFORNIA.

ROAD-BED CULTIVATOR.

1,178,880.

Specification of Letters Patent.

Patented Apr. 11, 1916.

Application filed June 22, 1915. Serial No. 35,722.

To all whom it may concern:

Be it known that I, WILLIAM R. SCOTT, a citizen of the United States, residing at Berkeley, in the county of Alameda and State of California, have invented certain new and useful Improvements in Road-Bed Cultivators, of which the following is a specification.

My invention relates to an implement or machine, for economically and efficiently treating a railway roadbed to secure its better maintenance, which implement or machine, from the nature of its work and result reached, may properly be termed a road-bed cultivator.

The object of my invention will be readily understood from a brief statement of the problem presented.

In the art of railroading one of the principal items of expense is the maintenance of track. A very substantial amount of the cost of track maintenance lies in keeping proper drainage to the ties and in keeping the ballast free from weeds. The reason for this excessive cost is due to the fact that all the work has to be done by hand, no suitable device being on the market for handling this phase of track maintenance.

It is a well-known fact that, owing to the constant rolling of locomotives and trains over the track, the entire weight is transmitted through the ties to that portion of the roadbed directly under the ties. Therefore, there is a tendency to pack the ballast or other track material under the ties very hard, and to settle the ballast around their ends, thereby preventing water from readily draining from under the tie, and causing it to churn with a pumping action, resulting in loose ties and uneven roadbed.

It is also a well-known fact that in rock or gravel ballast there is a tendency for the coarse gravel to roll to the bottom of the slope or toe line of the track section, leaving the finer ballast around the end of the tie and extending to the bottom thereof, all of which has a tendency to retard the drainage. My invention presents a solution of this problem, in that it provides a machine or implement capable of keeping the ballast free from weeds, and of so treating and manipulating it as to form it into and leave it in the best condition for drainage.

To this end my invention consists in the novel roadbed cultivator which I shall here-

inafter fully describe, by reference to the accompanying drawings, in which—

Figure 1 is a side elevation of my roadbed cultivator, showing the various operating members of one side thereof mounted upon a suitable supporting car. Fig. 2 is a plan view of the same, the operating members on one side being shown in position for use and those on the other side being indicated in position out of use. Fig. 3 is an end elevation showing the operating parts on each side, as in Fig. 2. Figs. 4 and 5 are, respectively, a side elevation and an end elevation of the plows of my cultivator, showing their attachment to the car frame. Figs. 6, 7 and 8 are, respectively, a side elevation, an end elevation, and a part sectional plan of the first scraper, and its operating mechanism.

In the drawings, in all of which like characters of reference indicate corresponding parts,—1 is a car, of any suitable form and size, its wheels 2 running on the rails 3 laid upon the ties 4 set in the roadbed 5.

The various members hereinafter described are divided into two identical sets, one set mounted upon each side of the car. Therefore, although I shall confine myself to a description of the elements appearing upon one side of said car, it is understood that such description applies equally to the elements upon the other side.

Mounted on the side of the car 1 are the depending guide brackets 6 upon which are slidably mounted for vertical adjustment the sleeves 7 carrying the connecting cross-bar 8. The outwardly or laterally extending arms 9 are pivotally mounted on the cross-bar 8, and carry at their outer ends the plow-beams 10 and 11 from which are carried respectively the plow-bottoms 12 and 13, set 95 with the mold-boards toward the rails.

It will be seen by reference to Figs. 1, 4 and 5 of the drawings, that the plow 12 is slightly in advance of, higher, and closer to the rail than the plow 13, the reasons for which will be hereinafter set forth. The arms 9, carrying the plow-beams 10 and 11, have been described as pivoted to the bar 8. The solid frame-work thus formed by the arms 9 and the plow-beams 10 and 11 can be raised or lowered at its outer end by the cylinder 14, containing a piston, not shown in the drawings, operable by any suitable fluid under pressure, the movement of said piston being communicated to the arms 9.

through the piston rod 15, and the cable, rope or line 16 running as shown over the several pulleys 17, 17' and 17" mounted upon the superstructure 18 of the car. A manually operated windlass 19 is provided to take the place of the cylinder 14 should any necessity for so doing arise.

Fixed to the side of the car 1 in the rear of the plow assembly just described, are the 10 guides 20. Bars 21 are arranged to slide vertically within said guides. These vertical bars 21 carry at their lower ends the vertically disposed scraper shoe 22 which is shown in Figs. 6, 7 and 8 of the drawings, 15 to be formed with a forward section 23 which lies parallel and close to the rail, the toe of said section being rounded up at its bottom edge, as at 24 in Fig. 6. The main body 25 of the shoe 22 has a horizontal lower 20 edge, and is set at an angle to the line of the rail. A cylinder 26 containing a fluid-operated piston, not shown in the drawings, is attached to the car frame 1 between the vertical bars 21, and is arranged to raise or 25 lower said bars 21, with the attached scraper 22, by means of the piston rod 27, and the cross head 28.

In the rear of the scraper assembly just described, are secured to the car 1 the fixed 30 vertical guides 29, shown particularly in Fig. 1. The carrying-bar 30 is adapted to slide in a vertical direction between the guides 29, and has the shaper 31 connected to its lower end by the vertical pivot 35 coupling or hinge 32. The shaper 31 consists of a vertically disposed plate or blade extending, when in use, in a substantially lateral direction from the side of the car, its lower or cutting edge being formed to 40 follow the cross-sectional contour of the roadbed. This lower edge therefore has a downwardly inclined portion 33, and extending from the outer and lower end thereof a horizontal portion 34. The outer 45 end of the shaper 31 is supported vertically from the upper end of the carrying-bar 30, by the adjustable brace rod 35, and it is supported laterally by the brace 36, which brace is pivoted at 37 to the back of the 50 shaper 31, and at 38 to an adjustable slide 39, working in the stationary horizontal guides 40 on the car. Thus by the movement of the slide 39, the shaper may be made to assume either an extended or a retracted 55 position, as shown in Fig. 2 of the drawings.

The carrying-bar 30, to which is attached in the manner described, the shaper 31, is provided with an inwardly extending bracket 41, which is connected by means of the rod 60 42 to the piston of a fluid cylinder 43, whereby said shaper 31 may be raised or lowered. A manually operated windlass 44 with the rope 45 running over the pulleys 46 is provided to take the place of the fluid cylinder 43, should necessity therefor arise.

A tank 47 is mounted on the car 1, to act as a storage reservoir for the fluid used in the operating cylinders 14, 26 and 43. This fluid is preferably air under pressure, and may be drawn from the usual air-brake system of the car. From the tank 47 the air or other fluid is distributed to the operating cylinders by means of the controlling valves 48 and the pipes 49, which are only partly indicated in the drawings, 75 though sufficiently so to indicate their function.

The coöperation of the several elements of my roadbed cultivator will now be described in order to show how the desired 80 result is attained. The car being in motion, the arms 9 carrying the plows 12 and 13 are lowered, until the plow 12 cuts a furrow in the roadbed adjacent to the ends of the ties 4, the bottom of said furrow being 85 slightly below the level of the bottoms of the ties. The gravel or other material of the roadbed is thus thrown by the plow 12 inwardly toward the rail and up onto the ends of the ties 4. The gravel at this point, 90 that is, adjacent to the ends of the ties, is, as before stated, finer than that farther down the slope of the roadbed, and it is a function of the upper plow 12 to remove this relatively fine gravel from the upper 95 part of the roadbed and pile it temporarily on the ends of the ties.

The plow 13, following below and outside of the plow 12, throws the relatively coarse gravel of the lower portion of the 100 slope of the roadbed up into the furrow made by the plow 12, the bottom of which furrow, as before stated, is slightly below the level of the bottoms of the ties. Thus free drainage is provided for that portion 105 of the roadbed immediately below the ties, through the coarse gravel thrown up by the lower plow 13 into the furrow made by the plow 12.

The horizontal scraper 22, following the 110 plows, is set, by its controlling means, to clear the tops of the tie-ends, the forward end 23 thereof running parallel and adjacent to the rail. The inclined portion 24 of said scraper 22 scrapes the relatively fine 115 gravel, which has been thrown up onto the tie-ends by the plow 12, off said tie-ends and over the edge of the roadbed, whereupon said gravel falls down into the lower furrow made by the plow 13. Thus by the 120 coöperative action of the two plows 12 and 13 and the scraper 22, the relatively coarse gravel at the lower part of the slope of the roadbed, and the relatively fine gravel at the upper part thereof, are made to change 125 places. Finally, the shaper 31, following the plows 12 and 13 and the scraper 22, by its position and the form of its lower edge, smooths out any inequalities in the slope of the roadbed left by the plows and the 130

scraper and forms said slope to the desired contour.

Inasmuch as similar members are mounted on both sides of the car, but controlled by separate mechanisms, the two sides of the roadbed may, or may not be treated simultaneously as convenience or necessity may direct. It will be seen moreover that on account of the adjustments and controlling means provided for the various members of my cultivator, said members may be made to operate successfully over irregularities in the roadbed, as, for example, on curves, where the outside rail is raised; and when obstructions are encountered, as, for example, culverts or bridge abutments, the plows and scrapers may be raised up to a vertical position, as shown in Fig. 3 of the drawings, and the projecting shapers may be swung rearwardly and inwardly toward the side of the car, as shown in Fig. 2 of the drawings.

While the particular form of roadbed cultivator as herein described is that which I regard as most practicable, nevertheless I am aware that changes and variations may be made in the form and arrangement of the component members, without in anyway affecting the elements of my invention, and I do not wish to be construed as limiting myself to the particular forms and arrangement herein described.

I claim:

1. In a railway roadbed cultivator, a car; means carried thereby and operating on the roadbed parallel with the rails and proximate to the ends of the cross-ties to turn the material toward and upon said tie ends, a second means carried by the car and operating on the roadbed parallel with the line of operation of the first named means and in the rear thereof, to turn the material into the vacancy left by said first named means; and means carried by said car and following said second named means for directing outwardly away from the rails and ties, the material turned upon them by the first named means.

2. In a railway roadbed cultivator, a car; means carried thereby and operating on the roadbed parallel with the rails and proximate to the ends of the cross-ties to turn the material toward and upon said tie ends, a second means carried by the car and operating on the roadbed parallel with the line of operation of the first named means and in the rear thereof, to turn the material into the vacancy left by said first named means; a third means carried by said car and following said second named means for directing outwardly away from the rails and ties, the material turned upon them by the first named means; and means carried by said car and following said third named means for leveling and shaping the roadbed,

beyond the ends of the ties, to its predetermined contour.

3. In a railway roadbed cultivator, a car; a pair of plows carried thereby, one of said plows being in advance of, out of line with, and at a different level from the other plow, the foremost, inner and higher plow being carried in position to make a furrow in the roadbed parallel with the rails and proximate to the ends of the cross-ties, the mold-board of said plow being so positioned as to throw the material toward and upon the ends of said ties, and the other plow being carried in position to make a second furrow parallel to the first and at the toe of the roadbed slope, the mold-board of said other plow being so positioned as to throw the material into the first furrow; and a scraper carried by said car behind said plows, in position to move over the tie-ends and remove and direct outwardly away from the rails and ties, the material thrown up by the inner plow.

4. In a railway roadbed cultivator, a car; a pair of plows carried thereby, one of said plows being in advance of, out of line with, and at a different level from the other plow, the foremost, inner and higher plow being carried in position to make a furrow in the roadbed parallel with the rails and proximate to the ends of the cross-ties, the mold-board of said plow being so positioned as to throw the material toward and upon the ends of said ties, and the other plow being carried in position to make a second furrow parallel to the first and at the toe of the roadbed slope, the mold-board of said other plow being positioned to throw the material into the first furrow; a scraper carried by said car behind said plows, in position to move over the tie-ends and remove and direct outwardly away from the rails and ties, the material thrown up by the inner plow; and a shaper blade carried by said car behind the scraper, in position to level and shape the roadbed, beyond the ends of the ties, to its predetermined contour.

5. In a railway roadbed cultivator, a car; means carried thereby and operating on the roadbed, parallel with the rails, for turning the material along a line proximate to the tie-ends inwardly toward and upon the ends of the ties, and turning the material along an outer line into the space left vacant by the turning of the material along the first line, and a scraper carried by the car behind said turning means, said scraper riding over the tie ends, its inner end extending parallel with the rails, and thence inclined outwardly to the rear, to remove and direct outwardly away from the rails and ties, the material turned inwardly from the first named line.

6. In a railway roadbed cultivator, a car; means carried thereby and operating on the

- roadbed, parallel with the rails, for turning the material along a line proximate to the tie-ends inwardly toward and upon the ends of the ties, and turning the material along 5 an outer line into the space left vacant by the turning of the material along the first line, means carried by the car behind said turning means for directing outwardly away from the rails and ties, the material thrown in 10 wardly from the first named line; a shaper blade carried by the car behind the said

directing means, said blade having a functional edge conforming to the predetermined contour for the roadbed; and means for adjusting the inclination of said shaper blade. 15

In testimony whereof I have signed my name to this specification in the presence of two subscribing witnesses.

WILLIAM R. SCOTT.
